UNITED STATES PATENT OFFICE.

HENRY C. CRONEMEYER, OF BEAVER, PENNSYLVANIA.

COOLING AND FRAGMENTING APPARATUS AND METHOD.

Application filed July 10, 1922. Serial No. 573,880.

To all whom it may concern:

Be it known that I, HENRY C. CRONEMEYER, residing at Beaver, in the county of Beaver and State of Pennsylvania, a citizen 5 of the United States, have invented or discovered certain new and useful Improvements in Cooling and Fragmenting Apparatus and Method, of which improvements the following is a specification.

10 My invention relates to improvements in method of and apparatus for cooling, solidifying, and fragmenting molten or substantially molten substances. It finds practical application in an appliance for speedily 15 cooling and solidifying the molten slag coming from a blast furnace or other furnace in such way that it shall be divided and discharged in pieces or lumps small enough that it may be readily handled and used, 20 without the labor heretofore necessary in breaking it up after it has cooled and solidified in the open air, or has been cooled by other devices now in vogue.

In the accompanying drawings Figure 1 25 is a medial, sectional plan view of the apparatus. Figure 2 is a sectional elevation on the line II—II of Figure 1. Figure 3 is an end view showing the driving mechanism. Figure 4 is a cross sectional elevation 30 on the line IV—IV of Figure 1.

Broadly considered, the apparatus embodies a box or tank structure or casing, to receive the molten slag, the walls of which are water-cooled, and within the structure, 35 and cooperating with its inner walls and with each other, there are arranged a plurality of spirally grooved rollers which, by their rotation, serve to transport the slag from the hot end or entrance end of the box 40 or casing to the opposite end where the cooled slag is discharged. In the course of such transportation the slag solidifies and is fragmented. The box or casing 1 is composed of side walls 2, 2, and end walls 3, 3, 45 preferably made in sections 4, which in this case are shown as castings having within them the pipes for the flow of the cooling water or other fluid. In a word, these sections are bosh plates. The water is introduced through a water main 5, from which branch pipes 6 lead to the pipes 7 in the walls of the chamber, and the water is discharged from the pipes 7 through the pipes 8 to the return main 9.

50 In the present case I have shown four spirally grooved rollers or drums 10; these

rollers are also shown to be castings having within and adjacent to their surfaces two sets of pipes 11 and 12, arranged as indicated, in the form of a double spiral, the pipes 60 11 following the protuberances or ridges upon the surfaces of the rollers and the pipes 12 the grooves or depressions in these surfaces. Water is supplied to these pipes from the main supply pipe 5 leading into 65 the hollow shaft of each roller and to the entrance chamber 13, and this water is discharged again through the hollow shaft at the opposite end of each roller into the discharge main 14. The rollers are so arranged relatively to each other that the protuberances and grooves of the rollers are in 70 register and the spaces or passes between adjacent rollers are of uniform width throughout. This may be accomplished 75 by forming the spirals upon the two rollers of each pair as spirals extending in the same direction and by rotating the two rolls of each pair in the same direction and further, as between pairs, making 80 opposite the directions in which the spirals extend and making opposite the directions of rotation also. The directions of rotation are indicated by the arrows I, Figure 85 3.

Though the corrugations upon the surfaces of adjacent rollers engage one another, or at least are in register, the roller surfaces do not actually touch, and the roller surfaces though arranged closely adjacent 90 do not touch the top, bottom, and side walls of the chamber. There are thus formed between the adjacent rollers and between the rollers and the chamber walls constricted 95 spaces through which the molten slag is impelled by the rotation of the rollers and is broken up as it cools and solidifies, and the rotation of the rollers at the same time serves to prevent clogging of these spaces, so that the slag impelling and cooling apparatus is essentially self-feeding. As 100 shown in Figure 3, the rollers are driven by means of a shaft 15, connected to a suitable source of power and having bevel gears 16 meshing with bevel gears 17 on counter-shafts 18. Counter-shafts 18 carry pinions 19, and these mesh with gears 20 on the shafts 21 of the rollers. At the opposite 105 end of the structure the discharge main 9 forms the base of the bearings of the roller shafts, and thus prevents overheating of 110 these bearings. The pipes 22 connecting

the water-supply pipe 5 with the roller shafts are preferably also provided with expansion joints 23.

The molten slag is fed to the tank through 5 the trough 24, the bottom of which is in open communication with the tank.

The operation of the apparatus in which my improvement in method is achieved, will be apparent from the foregoing description. 10 The molten slag is run into the machine through trough 24 (which extends across the width of the chamber) and enters the cooling chamber, the sides, top and bottom of which are water cooled. Within this 15 chamber rotate the four water-cooled rollers 10 with spiral grooves on their periphery. These rollers come close to the walls of the chamber, but do not touch them. Also the grooves and ridges of adjacent rollers 20 mesh, but do not touch. There are thus formed between the rotating rollers and the chamber walls a number of annular spaces, into which the molten mass flows from the water-cooled entrance hopper 24. As the 25 rollers 10 rotate, the spiral ridges force the material toward the discharge opening 25. The cross section of the grooves and the speed of rotation are so proportioned that the material is kneaded and crowded and 30 crushed and crumbled as it solidifies and is delivered in crumbled condition.

As the heat transmission between the material under treatment and the instrumentalities which engage it increases with their 35 movement, relative to each other, and with constantly changing surface contact, the heat absorption by the water in the rollers and in the chamber walls is rapid, and the molten slag is quickly cooled and solidified 40 and fragmented.

In addition to causing the slag to advance toward the discharge end of the machine, the spiral contour of the roller surfaces serves to prevent the formation of ridges of slag 45 on the chamber walls, but constantly sweeps the mass onward.

It will be apparent that this apparatus is susceptible of considerable modification. I have shown both the tank walls and the rollers in the form of castings. This is preferred 50 in order to give them sufficient strength to resist the heavy wear to which they are subjected, but it will be understood in some instances that the rollers may be hollow and 55 the tank walls also may be made up of hol-

low box-like sections of any other construction suitable to permit the necessary degree of cooling.

I have made this invention with the problem of cooling, solidifying, and crushing slag in mind,—particularly blast-furnace slag. But, having now described the invention, in that particular application, it remains to be remarked, that the apparatus may be employed to accomplish in continuous operation the rapid cooling, solidifying, and reducing to fragments of molten or substantially molten substances of various sorts,—including substances in plastic condition due to heat. This observation indicates that my invention is suitable for the treatment of slags from whatever source, whether blast furnace or otherwise, and is applicable to the treatment, not of by-products only, but even to the treatment of the metal itself, where fragmentation into lumps of moderate size and somewhat irregular form is desired or adequate for further ends.

I claim as my invention:

1. Solidifying and fragmenting apparatus 80 including a casing and two pairs of rollers mounted on parallel axes lying within a single plane and arranged within the casing, the rollers of each pair rotatable in the same direction and the direction of rotation as between the pairs being opposite, said rollers being provided with spiral surface corrugations, the corrugations of the two rollers of each pair being in register, and said rollers being spaced at intervals from the inner 90 wall of the casing and from one another.

2. A cooling and fragmenting apparatus 95 consisting of a casing composed of a plurality of water cooled boshes separately removable from a carrying frame, and a water cooled roller having a spiral surface corrugation arranged within said casing and spaced at an interval from the inner wall of the casing and rotatable within the 100 casing.

3. The method herein described of treating molten slag which consists in causing it to solidify, and subjecting it as it solidifies to crushing stress.

In testimony whereof I have hereunto 105 set my hand.

HENRY C. CRONEMEYER.
